UNITED STATES PATENT OFFICE

111,228

DESIGN FOR A BELT BUCKLE

Reuben Slote, Mount Vernon, N. Y., assignor to Slote & Klein, Inc., a corporation of New Jersey

Application June 27, 1938, Serial No. 78,092

Term of patent 3½ years

To all whom it may concern:

Be it known that I, Reuben Slote, a citizen of the United States, residing in the city of Mount Vernon, county of Westchester, and State of New York, have invented a new, original, and ornamental Design for a Belt Buckle, of which the following is a specification, reference being had to the accompanying drawing, forming part thereof.

I claim:

The ornamental design for a belt buckle, as shown.

REUBEN SLOTE.
